UNITED STATES PATENT OFFICE.

PHILIP A. MYERS, OF ASHLAND, OHIO, ASSIGNOR TO F. E. MYERS AND BRO., OF ASHLAND, OHIO, A COPARTNERSHIP.

PUMP-JACK.

SPECIFICATION forming part of Letters Patent No. 787,462, dated April 18, 1905.

Application filed August 6, 1904. Serial No. 219,701.

To all whom it may concern:

Be it known that I, PHILIP A. MYERS, a citizen of the United States, residing at Ashland, in the county of Ashland and State of Ohio, have invented certain new and useful Improvements in Pump-Jacks, of which the following is a specification, reference being had therein to the accompanying drawings.

This invention relates to pumping-jacks, and has for its object to provide an attachment for use in connection with an ordinary pump, such as is usually operated by a windmill or by hand at will. In those portions of the country where such pumps are employed to provide a supply of water reliance is usually placed upon the windmill as a motor to operate the pump; but extended periods of calm frequently occur, when this motive power is unavailable. In such periods provision is made for operating the pump from any suitable motor, such as a horse-power, gas-engine, or the like; and the particular object of my present invention is to provide a jack which shall be readily applied to any pump and firmly maintained in relation thereto, which will serve to transmit power received from the motor by means of a belt to the pump mechanism, and which shall be simple, inexpensive, and of high efficiency.

To these ends my invention consists in certain novel features, which I will now proceed to describe and will then particularly point out in the claims.

In the accompanying drawings, Figure 1 is a perspective view illustrating my improved jack applied to a pump. Fig. 2 is a similar view, showing the jack detached. Fig. 3 is a side elevation of the jack applied to the pump. Fig. 4 is an enlarged plan section taken on the line $\alpha\alpha$ of Fig. 3 and looking in the direction of the arrows. Fig. 5 is a detail view of the crank-arm detached. Fig. 6 is an enlarged detail sectional view showing the connection between the two members of the pitman; and Fig. 7 is a detail plan section similar to Fig. 4, but on a reduced scale, showing a modification.

In the said drawings, 1 indicates a pump as a whole, comprising the usual standard 2, pro-

vided with the base 3, by means of which it is secured to the usual platform or support 4. 5 indicates the piston-rod or windmill-bar, and 6 the handle for manual operation, which is shown disconnected in the accompanying drawings. These parts may be of any approved construction.

The jack comprises a standard 7 in the form of a hollow pillar open at one side, as clearly shown in Figs. 1 and 2, and having a base 8, which is also hollow and open at one side, said jack-standard and its base being of dimensions such that they will readily pass around and partly inclose the standard and base of the pump, as clearly shown in Figs. 1 and 3. The jack is secured to the platform or support 4, upon which the pump-standard is mounted independently of said pump-standard, preferably by means of bolts 9. The jack-standard is provided at its upper end with a bearing-sleeve 10, in which is mounted a shaft 11, provided with a gear-wheel 12. Said jack-standard is further provided with a bracket comprising an inclined plate 13, extending downward and rearward from the bearing-sleeve 10, and a vertical plate of web 14, connecting the body of the standard and said plate 13. This bracket supports a shaft 15 by means of a bearing-sleeve 16, and said shaft 15 is provided with a pinion 17, which meshes with the gear 12. The shaft 15 is further provided with a fast pulley 18 and loose pulley 19, by means of which power may be applied to rotate the shaft 15 from any suitable motor, such as a horse-power, gas-engine, or the like. The pinion 17 may be provided with a protective cap 20 to prevent the same from becoming clogged by ice or snow or any other cause. The shaft 11 projects beyond the bearing-sleeve 10 at each end, the gear-wheel 12 being mounted on one of said projecting ends, while the other projecting end has secured on it a crank-arm 21. (Shown in detail in Fig. 5.) The gear-wheel 12 and the crank-arm 21 are each provided with a plurality of apertures 22, arranged at different distances from the shaft 11, so that the throw or stroke of the pump may be readily adjusted. To this end two pitmen are employed,

each designated as a whole by the reference-numeral 23 and each provided at its lower end with a crank-pin 24, which may be secured in any one of the apertures 22 of the gear-wheel 12 or crank-arm 21. The upper ends of the pitmen 23 are connected to the piston-rod or windmill-bar 5 in any suitable manner, preferably by means of the same pin 25 which is employed to connect the pump-handle 6, said pin being readily removable to permit the connection of the pump-handle or of the pitmen, as desired. The pitmen 23 thus lie upon opposite sides of the pump when the jack is in place and operate upon the same with a practically vertical movement. Since pumps vary considerably in their dimensions and structure, it is necessary not only to regulate the stroke of the pitmen 23, but also to regulate the distance between the crank-pins 24 and the point of connection of the upper ends of said pitmen at 25. To this end the pitmen are each made in two parts, the one member, preferably the lower part, (indicated by the reference-numeral 26,) being in the form of a hollow sleeve internally threaded, into which is screwed the lower end of the other member, 27, which is correspondingly threaded at its lower portion. By screwing the member 27 further in the member 26 the pitman may be shortened, while a reversal of this operation will lengthen the pitman. A lock-nut 28, mounted on the member 27, may be screwed up against the end of the member 26 to hold the parts firmly in the position to which they may be adjusted. The jack thus organized may be readily applied to any commercial pump of the general class in connection with which it is to be used, and this application is effected by placing the jack upon the same platform or support that the pump is mounted on, moving it up to the pump until it partially surrounds and incloses the same, as shown more particularly in Fig. 1 of the drawings. Preferably the jack is moved up to the pump until the bearing-sleeve 10 at the top of the jack-standard comes into contact with the pump-standard, so as to have a firm bearing against the same. The jack-standard is then secured to the platform or support, this being accomplished entirely independently of the pump, with which the jack-standard does not require to be connected, thus allowing the pump to remain undisturbed just as it was originally set in the well, the jack-standard sustaining itself entirely by its independent base, which is separately bolted to the platform or support. The widely-extending base of the jack-standard, practically surrounding the pump-base on three sides thereof, gives a firm and extensive support for the jack, which support is supplemented when necessary by the bearing of the sleeve 10 against the pump. This construction brings the shaft 10 so close to the central vertical line of the pump that the working strains on

the pitmen and pump-rod are practically in line with the travel of this latter part. It will be seen, therefore, that the jack can be readily and quickly set up and fastened in position without connecting in any way with the pump, thus requiring no special construction for this latter purpose and increasing the range of pumps to which the device is applicable, while the proper alinement of the jack relative to the pump may be readily effected.

Modifications of the structural details will readily suggest themselves to those skilled in the art, and I therefore do not wish to be understood as limiting myself to the precise details of construction hereinbefore described, and shown in the accompanying drawings. For instance, although it is not necessary, as I have already stated, to connect the jack-standard to the pump-standard it may be found desirable to do so on certain occasions, in which case such connection may be readily effected, as shown in Fig. 7, by the employment of a clip or U-bolt 29, the bend of which may embrace the pump-standard 2, while its threaded ends pass loosely through lugs 30 on the sleeve 10 and are provided back of said lugs with nuts 31, which bear against the lugs and clamp the pump-standard and jack-standard firmly together. Furthermore, the train of gearing between the crank-shaft and pulley-shaft may be obviously modified as occasion may require.

Having thus fully described my invention, what I claim as new, and desire to secure by Letters Patent, is—

1. A pumping-jack comprising a hollow standard and base, open at one side to receive the pump standard and base, and adapted for independent connection to the platform or support on which the pump is mounted and gearing mounted on said standard and adapted for connection with the pump-rod to convert the rotatory motion of said gearing to a reciprocating motion of the pump-rod, substantially as described.

2. A pumping-jack comprising a hollow standard and base, open at one side to receive the pump standard and base, and adapted for independent connection to the platform or support on which the pump is mounted, said jack-standard being provided with a bearing-sleeve at the top thereof adapted to bear against the pump-standard, a crank-shaft mounted in said bearing-sleeve, and pitmen connected with said crank-shaft and adapted to be connected to the pump-rod, substantially as described.

3. The combination, with a pump having a standard, rod and base, and a platform or support to which said base is secured, of a pumping-jack comprising a hollow standard and base, open at one side to receive the pump standard and base, said jack-standard having its base secured to the platform or support independently of the pump, and gearing mount-

- ed on said standard and connected with the pump-rod so as to convert the rotatory motion of the gearing to a reciprocating motion of the pump-rod, substantially as described.
- 5 4. The combination, with a pump having a standard and base, and a platform to which said base is secured, of a pumping-jack comprising a hollow standard and base, open at one side to receive the pump standard and base, said jack-standard having its base independently secured to the platform, said jack-standard being provided with a bearing-sleeve at its upper end arranged to bear against the pump-standard, a crank-shaft mounted in said bearing-sleeve and provided with pitmen adapted to be connected to the pump-rod, a second shaft mounted on said jack-standard and provided with a driving-pulley to receive a belt, and gearing connecting said shafts, substantially as described.
- 10 5. A pumping-jack comprising a hollow standard and base, open at one side to receive
- the pump-standard and its base, said jack-standard having a bearing-sleeve at its upper end, a second bearing-sleeve parallel with the first bearing-sleeve, said jack-standard also having a bracket supporting said second bearing-sleeve and consisting of a plate connecting said sleeves and a vertical plate connecting the first-mentioned plate and the jack-standard body, a crank-shaft mounted in one of said bearing-sleeves, pitman connected with said crank-shaft and adapted to be connected to the pump-rod, a shaft mounted in the other bearing-sleeve and provided with a pulley, and a train of gears connecting said shafts, substantially as described.

In testimony whereof I affix my signature in presence of two witnesses.
